WITNESS:

John Donovan

John Baloyan
INVENTOR
BY *Victor J. Evans*

ATTORNEY

UNITED STATES PATENT OFFICE.

JOHN BALOYAN, OF WASHINGTON, DISTRICT OF COLUMBIA.

THUMB TACK.

Application filed August 6, 1925. Serial No. 48,662.

This invention relates to improvements in thumb tacks, one of the objects of the invention being to provide a pad or washer for the tack for increasing its gripping action on the sheet or other object being held thereby.

Another object of the invention is to provide a hand engaging part on the washer which facilitates handling of the tack and its removal from the board or other support into which it is pressed.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a fragmentary view of a board showing the invention in use.

Figure 2 is an enlarged view of a tack with the attachment thereon.

Figure 3 is a view of the attachment itself.

Figure 4 is a section on line 4-4 of Figure 2.

Figure 5 is a section on line 5-5 of Figure 2.

Figure 6 is a sectional view showing a modification.

As shown in these views, I provide a washer or pad 1 for engaging the under face of the head of a thumb tack, such as shown at 2, so that this pad will frictionally engage the sheet or other object being held by the tack and will thus prevent movement of the object on the board, or other support. The pad is provided with a restricted rounded extension 3 which forms a handle and enables the tack to be easily pulled from the board or other support. The pad or washer can be used on the various kinds of tacks now on the market and it can be formed of different materials, though I prefer to form it of rubber or a composition of rubber which may be provided with a cloth facing.

Figures 1 to 5 show the invention in use

with a tack, the point 6 of which is cut from the head 7 thereof, the point being of arrow shape, so that it forms the shoulders 8 which are spaced from the head of the tack. 55 The pad or washer is perforated, as at 9, to receive the point and after being stretched over the large part thereof, the portions of the pad will contract and engage the reduced part of the point between the shoulders 8 60 and the head so that the pad will be held in place by said shoulders.

In the modification shown in Figure 6, the point 6' is suitably fastened to the head 7' of the tack and this point forms an annular shoulder 8' which holds the pad in place. Thus in the two forms shown, the pad is held in place by the shoulders formed on the pointed part of the tack, but as before stated, the pad can be held in place in any 70 suitable manner, or it can be simply placed on the pointed part of a tack and held thereon by friction.

As will be seen, this invention not only increases the gripping effect of a tack on an 75 object, but also facilitates handling of the tack and enables it to be pulled from the board by a pull on the handle 3, thus obviating the use of the finger nails or a tool in removing the tack.

It is thought from the foregoing description that the advantages and novel features of my invention will be readily apparent.

I desire it to be understood that I may make changes in the construction and in the 85 combination and arrangement of the several parts, provided that such changes fall within the scope of the appended claim.

What I claim is:

A thumb tack having a head and a point 90 projecting therefrom, a pad engaging the under face of the head, the pointed part of said tack adjacent its juncture with the head thereof being reduced to provide shoulders underlying the head for holding the pad 95 associated with said tack against the head, and a restricted ex-peripheral portion formed on said pad providing a handle therefor.

In testimony whereof I affix my signature.

JOHN BALOYAN.
